DISPLAY BOX FOR WATCHES AND THE LIKE

Francis E. Blod, New Canaan, Conn., assignor to Fanning Manufacturing Company, Needham Heights, Mass., a corporation of Massachusetts

Application Oct. 8, 1956, Serial No. 43,261

Term of patent 14 years

(Cl. D80—5)

Fig. 1 is a perspective view of a display box for watches and the like showing my new design;

Fig. 2 is a side elevational view thereof;

Fig. 3 is a top plan view of Fig. 1;

Fig. 4 is a front elevational view of Fig. 1;

Fig. 5 is a bottom plan view of Fig. 1; and

Fig. 6 is a rear elevational view of Fig. 1.

I claim:

The ornamental design for a display box for watches and the like, as shown.
